UNITED STATES PATENT OFFICE

2,421,712

BUTTONHOLE SEWING MACHINE

Walter E. Nichols, Milton, Mass., assignor to The
Reece Corporation, a corporation of Maine

Application January 9, 1943, Serial No. 471,843

3 Claims. (Cl. 112—252)

1

This invention relates to sewing machines, and especially to buttonhole sewing machines of the type known as "straight hole machines" such as those described in Patents Nos. 714,284, November 25, 1902; 749,776, January 19, 1904; 1,088,652, February 24, 1914; 1,402,073, January 3, 1922; and 1,483,307, February 12, 1924.

The invention relates particularly to an improvement in thread cutting or trimming mechanisms for machines of this and other types in which the trimming mechanism is operable upon the completion of the stitching operation to set the final stitch and then to cut or trim the thread.

Buttonhole sewing machines of the "straight hole" type include a cutter for cutting the buttonhole slit substantially upon the completion of the stitching operation and another cutter operable immediately thereafter to sever or trim the sewing thread. In some such machines, the buttonhole cutter is timed to operate just prior to the completion of the sewing cycle, usually during the formation of the last stitch, and the thread trimmer to operate immediately upon the completion of the last stitch and the stopping of the machine. In many such machines the buttonhole cutter and the thread trimmer are obliged to operate in intersecting or closely adjacent paths. Normally the buttonhole cutter completes its operation and is retracted or raised just prior to the operation of the thread trimmer, but if the buttonhole cutter should for some reason become jammed in the work and fail to rise promptly, there is a possibility of its being struck by the thread trimmer with resulting damage to either or both of them.

Attempts have heretofore been made to avoid interference of this sort by making the operation of the thread trimmer automatically contingent upon the retraction of the buttonhole cutter, as by providing an operative connection, between the trimmer and its actuating means, which is automatically disabled or uncoupled except when the buttonhole cutter is in retracted position. Even with such an arrangement, however, it is possible, due to wear, roughness, and sticking of the parts, for the trimmer actuating means to cause a premature operation of the trimmer when the buttonhole cutter has been moved partly out of its fully retracted position but before completion of its buttonhole cutting stroke.

In machines of the "straight hole" type referred to, as heretofore constructed, the thread trimmer received its movement solely from the momentum of the machine at the time when the resiliency of the stopping mechanism allowed a

2

slight continued movement, usually termed "overthrow," and which is, in effect, a jolt or jar given at the time when the moving parts became locked. This dependence, for the operation of the thread trimmer, upon the stopping impact, "overthrow," or momentum of the machine, which may vary considerably under variable conditions, has resulted in unreliable and uneven trimming.

The object of the present invention is to avoid the possibility of premature operation of the thread trimmer, and interference between the latter and the buttonhole cutter, as aforesaid, and to provide means for operating said trimmer with a uniform, positive action, consistently and absolutely contingent upon the cutting operation and subsequent retraction of said cutter, independent of the impact of the stopping mechanism, and unlimited by the momentum of the machine.

The invention will best be understood from the following description of an illustrative embodiment thereof shown in the accompanying drawings.

In the drawings:

Fig. 1 is a view in side elevation, partly in section and partly broken away, of a machine embodying the present invention, showing the parts in the positions they occupy when the thread trimmer is in operation.

Fig. 2 is a perspective view of the thread trimmer and associated parts.

Fig. 3 is a plan view of the machine of Fig. 1, partly in section and partly broken away.

Fig. 4 is a fragmentary view in end elevation as viewed from the right in Figs. 1 and 3.

The machine shown in the drawings may, as to its general organization, be similar to those described in the patents above referred to. It comprises a bed 14 from which rises a standard 15 carrying an overhanging arm 16 spaced above the bed. The work W is carried by a work clamp or holder comprising a clamp plate 17 and cooperating clamping arms 18, said work holder being movable as a unit over the bed, by mechanism generally indicated at 19, in order to position the stitches along the sides of the buttonhole. The stitch-forming instrumentalities comprise an eye-pointed needle 20 above the work and cooperating loopers or equivalent under thread mechanism or handling devices 21 below the work, there being a throat plate 22 carried by the bed 14 and having an opening through which the needle operates. The needle 20 is carried by a needle bar 23 which is longitudinally and vertically reciprocated, by means generally indicated at 24, in a needle bar guide 25, means, not shown, be-

ing provided for oscillating said needle bar guide alternately in opposite directions transversely to the direction of feed of the work clamp between successive strokes of the needle to position the depth stitches. The thread *t* is taken from a suitable source and passes to the needle eye through a take-up *26* and suitable tension devices *27* and *28*, after which it passes through the work and throat plate to the loopers *21*. A main shaft *29* journaled in suitable bearings in the bed has power applied thereto by a belt *30* alternatively engageable with fast and loose pulleys *31* and *32* under the control of a belt shifter *33*. The belt shifter *33* constitutes an extension of a stop member or arm *34* carried by an oscillating and longitudinally movable rock shaft *35* mounted for oscillation and a limited longitudinal movement in the bed *14*. Associated with the sliding rock shaft *35* is a spring *36* (Fig. 3) surrounding said shaft and interposed between a collar *37* and one of the bearing brackets or ears *38* in which said shaft is mounted, said spring tending normally to move said shaft toward the right in Fig. 3. Slidably mounted in the stop arm *34* is a stop element or bolt *41* normally urged toward the right in Fig. 4 by a spring *42*. At its end the bolt *41* is formed with a nose *43* which is in the path of movement of a cam *44* fast on the shaft *29* when the shaft *35* is in the longitudinal position to cause the belt shifter *33* to engage the belt *30* with the loose pulley *32*. Cam *44* has a concentric portion *a*, a rise *b*, a notch *c* and a stop shoulder *d*, arranged to engage the nose *43* in the order named when the shaft is rotated in the direction of the arrow in Fig. 4. A spring-pressed plunger *45* carried by the upright standard *15* engages the stop arm *34* and tends to turn said arm and the rock shaft *35* in a clockwise direction as shown in Fig. 4 to press the nose *43* against the periphery of the cam *44* when said nose lies in the path of movement of said cam. A starting lever *46* is secured to a rock shaft *47* and is normally urged clockwise in Fig. 1 by a spring *48*. One arm *49* of said lever is connected to a treadle *T*, as by linkage *50*, and another arm *51* is adapted to engage the collar *37* and move the shaft *35* to the left in Fig. 1 when the treadle is depressed.

A detent *52* is adapted to engage a notch *53* in said shaft *35* to hold said shaft in its left-hand position during a sewing operation, other means, (not shown) serving to automatically release said detent at the beginning of the last stitch-forming cycle.

The buttonhole cutter *54* is carried by a lever *55* journaled on a short stud shaft *56* supported in the bed, said lever having an arm *57* carrying at its end a sleeve *58* in which is journaled a stud *59* having at one end a sleeve portion *60* which receives a stud *61* extending inwardly from the stop arm *34*.

The combined stitch setting and thread trimming element *74* is guided in ways in the bed *14* immediately below the throat plate *22* and between the latter and the loopers *21* (see Fig. 2). The element *74* is provided with an opening *75* adapted to receive a stud *76* carried by an arm *77* fast on one end of a rock shaft *78* journaled in suitable bearings in the bed *14*. At the completion of the last stitch forming cycle, and substantially coincidentally with the stopping of the machine, said element is moved from its normal retracted position shown in dotted lines in Fig. 2 into engagement with the thread loop as shown in the full line position in Fig. 2.

Except as hereinafter pointed out, or as they enter into combination with parts hereinafter described, the parts above referred to form no portion of the present invention and may be substantially as more fully described in the above mentioned patents.

Pivoted at *62* in the wall of the upright *15* is a clamp raising lever having one arm *63* extending to the exterior of the upright and formed to constitute a finger piece or hand lever and another arm *64* extending into the upright into a position to engage an extension *65* of the lever *66* which carries the clamp arms *18*. By moving the finger piece *63* inwardly (to the left in Fig. 1) the clamping arms *18* may be raised against the tension of the spring *67* to release the work. Conversely, when the clamp closes under the influence of the spring *67*, the arm *64* is moved upwardly and the finger piece *63* moved outwardly (to the right in Fig. 1). Pivoted at *68* to the arm *64* is a depending link *69* carrying a catch *70*. The link *69* is normally urged by a spring *71* in the direction to cause the catch *70* to engage a lug *72* carried by the arm *57* of the buttonhole cutter lever *55*. Consequently, when the buttonhole cutter *54* rises, the arm *64* is normally drawn downwardly to open the work clamp. The catch *70* may, however, be disengaged from the lug *72* by a trip finger *73* secured to the shaft *47*. The trip finger *73* is moved into a position to move the link *69* to the left (Fig. 1) and thereby disengage the catch *70* from the lug *72* when the treadle *T* is depressed, so that depression of the treadle to start the machine serves to disconnect the clamp and the buttonhole cutting mechanisms and permit the clamp to close.

The shaft *78* has secured thereto, at a point intermediate its ends, an arm *79* pivotally connected by a link *80* to the arm *81* (see particularly Fig. 4) of a bell crank *82* pivoted at *83* to a bracket *84* (see also Figs. 1 and 3) secured as by a screw *85* to the underside of the bed *14*. The other arm *86* of the bell crank *82* is pivotally connected by a link *87* to the arm *64* of the clamp raising lever. Consequently, when the lever arm *64* rises, the trimmer *74* is retracted, and when said lever arm is drawn downwardly, the trimmer is advanced into the position shown in full lines in Fig. 2.

In operation, the operator starts the machine by depressing the treadle *T* to rotate the starting lever *46* counterclockwise and move the rock shaft *35* to the left in Fig. 1 to shift the belt *30* from the loose pulley *32* to the fast pulley *31* and move the nose *43* out of the path of movement of the cam *44*, said shaft *35* being retained in this position until the beginning of the last stitch-forming cycle by the engagement of the detent *52* with the notch *53*. Depression of the treadle also causes the trip finger *73* to disengage the catch *70* from the lug *72*, thereby permitting the work clamp to close under the influence of the spring *67*, raising the lever arm *64*, and retracting the trimmer *74*. The treadle is then released, permitting the spring *48* to restore the lever *46* and trip finger *73* to the position shown in Fig. 1. When the detent *52* is withdrawn from the notch *53* at the beginning of the last stitch-forming cycle, the spring *36* causes the shaft *35* to move toward the right in Fig. 1 to shift the belt *30* from the fast pulley *31* to the loose pulley *32* and again bring the nose *43* into the path of movement of the cam *44*. During the formation of the last stitch, the

machine runs under its own momentum, and the nose 43 follows the periphery of the cam 44 until it is engaged by the rise b of said cam, whereupon the stop-arm 34 is lifted against the action of the spring pressed plunger 45. This lifting of the stop arm 34 operates, through the stud 61 and its connection with the arm 57 of the lever 55, to lift said arm 57 and thereby advance or depress the buttonhole cutter 54 and cause the same to cut the buttonhole slit. At the same time, the lifting of the arm 57 permits the link 69, under the influence of the spring 71, to move the catch 70 into a position to be engaged by the lug 72 when said arm is again lowered. Thereafter, the nose 43 drops off the rise b of the cam 44, and, under the influence of the spring pressed plunger 45, enters the notch c, this movement causing the buttonhole cutter 54 to be retracted or raised to its original or inoperative position. As the lever 55 is raised, the arm 57 is lowered, and the lug 72 engages the catch 70 in the link 69 and pulls downwardly on said link, which in turn depresses the arm 64 of the clamp raising lever 63. As the arm 64 is depressed, it operates through the link 87, bell crank 82, link 80 and arm 79 to rotate the shaft 78 clockwise in Fig. 4. This rotation of the shaft 78 operates, through the arm 77 and stud 76, to advance the trimmer 74 from the position shown in dotted lines in Figs. 2 and 3 to that shown in full lines in the same figures, this movement acting to set the stitch and trim or cut the thread loop.

It will be observed that the trimmer is operated from the buttonhole cutter lever during the rise, or retraction, of the cutter, and that the connections for operating the trimmer (including the link 69, catch 70 and lug 72) are disabled or disrupted when the machine is started and are not restored until the cutter has descended on its cutting stroke and subsequently rises. Therefore, the trimmer 74 cannot be prematurely operated; it is operated only when the buttonhole cutter 54 has completed its cutting stroke and has been raised out of the work and is consequently out of the path of movement of said trimmer. The spring pressed plunger 45 is the means used to raise the buttonhole cutter lever 55, and is also the source of power for actuating the trimmer 74, the arm 57 of the lever 55 and the arm 64 of the clamp raising lever serving as a part of the system of linkage connecting the spring pressed plunger 45 and the trimmer 74.

The use of the spring-pressed plunger 45 instead of the stopping mechanism for furnishing the power for operating the trimmer is an improvement of considerable advantage. It has been found in practice that the cutting of a relatively small buttonhole requires less force than the cutting of a large buttonhole. If the cutting operation takes a larger proportion of the power supplied by the momentum of the machine, it correspondingly leaves less for the operation of the trimming mechanism and may result in incomplete operation of the trimmer, and conversely, when the cutting operation requires a small part of the force supplied by the momentum, the remaining larger force of the momentum, if it is not absorbed by readjustment of the spring loaded plunger 45, will increase the wear and shock on the stop motion parts. If the momentum of the machine is used to operate the trimmer, the variation in the size of the buttonhole cut tends, therefore, to cause a corresponding variation in the operation of the thread trimmer.

Very careful machining, smooth surfaces, frequent lubrication, and adjustment of the spring loaded plunger 45 to balance the amount of momentum necessary for trimming and stopping are required if the momentum of the machine, acting through the stopping mechanism, is to be successfully used to operate the trimmer. Any roughness or irregularity of the cam 44, for instance, tends to cause the trimmer to receive its impulse simultaneously with the movement of the buttonhole cutter, and these variations in operation are, of course, apt to be increased as the parts begin to wear. The utilization of the spring pressed plunger 45 as a source of power for the operation of the trimming mechanism, however, provides a constant, unfluctuating force, the application of which to the trimming mechanism is always contingent upon the proper elevation of the button hole cutter 54 due to the fact that a part of the cutter operating mechanism forms a link in the chain of elements connecting the plunger and the trimmer.

The connection with the arm 64 of the clamp raising lever also provides for operation of the trimmer independently of the automatic operation of the machine. If, for instance, the operator wishes to inspect the work or remove it for any reason before the completion of a sewing operation, he can stop the machine and move the finger piece 63 inwardly to raise the clamps and release the work. Formerly, the work was held by the thread, but in the machine of the present invention the thread is trimmed as the clamps are raised, allowing the operator to move the work freely or remove it entirely.

I claim:

1. In a straight-hole button-hole sewing machine having a single cycle of operation during which the sewing is done and the button-hole is cut and the thread is severed, in combination, a button-hole cutter, a work clamp, clamp raising means, a thread trimmer, means operative during the formation of the last stitch to depress the button-hole cutter to cut a slit in the work, means operative thereafter to retract said button-hole cutter, a releasable connection between said button-hole cutter and said work clamp raising means, means for releasing the connection when the machine is started, means for re-establishing the connection when the button-hole cutter is depressed, and means connecting the clamp raising means and the trimmer, said releasable connection after the button-hole cutter is depressed being operative during the rise of the cutter to transmit force derived from the cutter retracting means directly to the clamp raising means and acting through said last named means to move the trimmer to sever the thread.

2. In a straight-hole button-hole sewing machine having a single cycle of operation during which the sewing is done and the button-hole is cut and the thread is severed, in combination, a button-hole cutter, a work clamp, clamp raising means, a thread trimmer, means operative during the formation of the last stitch to depress the button-hole cutter to cut a slit in the work, as the needle rises on the last up-stroke, means operative thereafter to retract said button-hole cutter, a releasable connection between said button-hole cutter and said work clamp raising means, means for releasing the connection when the machine is started, means for re-establishing the connection only when the button-hole cutter is depressed, and means connecting the clamp raising means and the trimmer, said releasable

connection after the button-hole cutter is depressed being operative only during the rise of the cutter to transmit force derived from the cutter retracting means directly to the clamp raising means and acting through said last named means to move the trimmer to sever the thread.

3. In a straight-hole button-hole sewing machine having a single cycle of operation during which the sewing is done and the button-hole is cut and the thread is severed, in combination, a button-hole cutter, a work clamp, clamp raising means, a thread trimmer, means operative during the formation of the last stitch to depress the button-hole cutter to cut a slit in the work, as the needle rises on the last up-stroke, means operative thereafter to retract said button-hole cutter, a releasable connection between said button-hole cutter and said work clamp raising means, means for releasing the connection when the machine is started, means for re-establishing the connection only when the button-hole cutter

is depressed, and means connecting the clamp raising means and the trimmer, said releasable connection after the button-hole cutter is depressed being operative only during the last part of the rise of the cutter to transmit force derived from the cutter retracting means directly to the clamp raising means and acting through said last named means to move the trimmer to sever the thread.
